CLAIM

The ornamental design for the massage machine, as shown and described.

DESCRIPTION

FIG. 1 is a view in perspective of a massage machine showing my new design;

FIG. 2 is a front elevational view thereof;

FIG. 3 is a rear elevational view thereof;

FIG. 4 is a view in side elevation thereof;

FIG. 5 is a view in side elevation opposite of that shown in FIG. 4;

FIG. 6 is a top plan view thereof; and,

FIG. 7 is a bottom plan view thereof.

The broken line showing is for illustrative purposes only and forms no part of the claimed design.
